Inventor.

James. D. Black.

UNITED STATES PATENT OFFICE.

JAMES D. BLACK, OF BOSTON, MASSACHUSETTS, ASSIGNOR TO HIMSELF AND EZEKIEL HALLET, JR., OF SAME PLACE.

BOOT-CRIMPING MACHINE.

Specification of Letters Patent No. 23,977, dated May 10, 1859.

To all whom it may concern:

Be it known that I, JAMES D. BLACK, of Boston, in the county of Suffolk and State of Massachusetts, have invented certain new and useful Improvements in Boot-Crimping Machines, of which the following is a full, clear, and exact description, reference being had to the accompanying drawings, making part of this specification, in which—

10 Figure 1 is a view of a boot crimping machine with my improvements attached. Fig. 2 detail to be referred to hereafter.

In boot crimping machines as ordinarily constructed, where the "hitch-on" is raised by the hand of the operator to take up the slack of the leather as the crimping proceeds, the device by which it is operated is attached rigidly to the top of the brake; this endangers tearing off the corners of the 20 leather which are held in the "hitch-on" if the leather should adhere to the jaws of the machine when the brake is raised.

To remedy this is the object of the first part of my invention, which consists in supporting the device by means of which the "hitch-on" is raised, upon a spring bearing which may yield should the leather stick in the jaws of the machine, and thus prevent the "hitch-on" from tearing off the corners 30 of it.

The second part of my invention consists in an improved "hitch-on" which will be hereafter more fully described.

That others skilled in the art may understand and use my invention I will proceed to describe the manner in which I have carried out the same.

In the said drawings A is the stand, B the jaws which are adjusted at the proper 40 distance apart by set screws *a*. C the brake which is pivoted at *b* to a short standard *c* rising from the stand A. To the top of the brake C is secured a block *d* from which rises a rod *e* over the top of which fits a cap *f* that slides up and down on the rod *e* for a short distance and is supported by a spiral spring *g* surrounding the rod. A standard *h* attached to the block *d* has a slot *i* near its top, in which slides a pin *m* projecting from 45 the cap *f*, this serves to steady the cap and keep it in a vertical position. In the top of the cap *f* is pivoted at *k* the lever *D* over the short end of which is hung a cord *l*, the other end of the cord being attached to the

"hitch-on" E (shown detached in Fig. 2). 55 This "hitch-on" consists of a saddle *n* to which the cord *l* is fastened, and which embraces and slides up and down on the brake C, being guided by pins *5* in the brake. To this saddle *n* is pivoted at *6* on each side a 60 jaw *p* the lower end of which grasps the corner of the leather to be crimped between the jaw and the lower end of the saddle *n*. A screw *o* passes through the top of one of these jaws *p* and rests against the other 65 lever, so that by turning the screw the lower ends of these jaws may be caused to close tightly upon the corners of the leather. A spiral spring *r* surrounds the screw *o* between the two jaws, and presses the upper 70 ends of them apart. A ratchet *u* on the cap *f* and a pawl *s* pivoted to the lever *D* serve to retain this lever as it is pressed down, and to hold up the "hitch-on" E as the slack of the leather is taken up. The spring 75 *g* is made only strong enough to enable the operator to take up the slack of the leather, but not to tear it.

The following is the operation of my improved crimping machine. The leather after 80 being cut of the proper size is placed beneath the brake C, its corners are brought up to the "hitch-on" E and are secured in its grasp. To effect this it is only necessary to bear over the tops of the jaws *p*, in the 85 direction indicated by the arrow (Fig. 2). This opens the jaw on this side as shown in red Fig. 2 for the reception of the corner of the leather; the other jaw *p* is then pushed in the direction contrary to the arrow, which 90 opens it in a similar manner. When the leather has been inserted into these jaws and they are released from the hand, the spring *r* closes the jaws, but to give them a firmer hold of the leather the screw *o* is 95 turned up to tighten them. As the crimping proceeds the lever *D* is depressed, this raises the "hitch-on" E and takes up the slack of the leather, the pawl *s* and ratchet *u* retaining what is gained. Now in this 100 crimping process, should the leather which is being operated upon adhere to the inner sides of the jaws B of the machine, and leave the brake C its corners would be liable to be torn off by the "hitch-on" E as the 105 brake C is raised, if it were not for the yielding of the spring *g* beneath the cap *f* which is compressed and relieves the strain

on the leather. Otherwise the operator might tear off the corners and spoil the piece of leather before he discovered that it had stuck to the jaws B.

- 5 With the "hitch-on" E arranged as above described the operator can insert the corners of the leather into the jaws more conveniently than with any other arrangement of "hitch-on" with which I am acquainted, as the spring r holds one jaw shut on one corner of the leather while the other corner is being inserted into the other jaw, it then only requires a few turns of a single screw to secure both jaws to the leather.
- 10
- 15 In lieu of placing the spring g beneath the bearing of the pivot h as above described, a spring may be interposed between the "hitch-on" and the device by which it is raised, which latter may then
- 20 be pivoted rigidly to the brake C.

I do not claim raising the "hitch-on" by a spring, as that is not new, but

What I do claim as my invention in machines for crimping boot legs, in which the "hitch-on" is raised by the hand of the 25 operator, is—

1. Pivoting the device by which the "hitch-on" is raised, to a spring block or its equivalent, for the purpose set forth.

2. I claim the peculiar construction of 30 "hitch-on" herein described, the movable jaws p being temporarily closed upon both sides by a spring r so that they may be separately opened as set forth for the insertion of the leather, and may be permanently closed 35 by a single screw as described.

JAMES D. BLACK.
